By Clarence O'Brien
Attorney

UNITED STATES PATENT OFFICE

FRANK BORRIELLO, OF EVERETT, MASSACHUSETTS

GARMENT HANGER

Application filed October 21, 1931. Serial No. 570,189.

The present invention relates to new and useful improvements in garment hangers and has for its primary object to provide, in a manner as hereinafter set forth, a device of this character embodying a novel construction, combination and arrangement of parts through the medium of which a coat or similar garment and a pair of trousers may be hung thereon in a convenient manner.

10 Other objects of the invention are to provide a garment hanger of the character described which will be simple in construction, strong, durable, efficient and reliable in use and which may be manufactured at low cost.

15 All of the foregoing and still further objects and advantages of the invention will become apparent from a study of the following specification, taken in connection with the accompanying drawing wherein like characters of reference designate corresponding parts throughout the several views, and wherein:—

20 Figure 1 is a view in elevation of a garment hanger in accordance with the present invention.

25 Figure 2 is a detail view in perspective showing the means for connecting trousers supporting elements to the main frame.

30 Figure 3 is a view in vertical cross section showing the means for connecting the trousers supporting elements to the main frame and for actuating said elements.

35 Referring now to the drawing in detail, it will be seen that the garment hanger constituting the present invention comprises a substantially triangular wire frame which is designated generally by the reference numeral 1, said frame being formed from a single length of wire bent in a manner to provide the upwardly converging arms 2 and a connecting portion or bar 3. At their upper ends, the arms 2 are bent in a manner to provide the angular portions 4. The end portions of the wire are twisted together, as at 5, to connect the arms 2. One end portion of the wire extends beyond the twist 5 and is bent to provide a supporting hook 6. As will be apparent, the frame 1 is adapted to receive a coat or similar body garment.

40 At spaced points the bar 3 of the frame 1

has formed therein the substantially V-shaped indentations 7. A pair of wires 8 are bent upon themselves around the angles 4 of the arms 2 and the folds of said wires 8 are then twisted upon themselves, as at 9. 55 The thus folded and twisted wires 8 are then twisted upon each other, preferably, but once as at 10 and extend from the twist 10 downwardly and outwardly toward the indentations 7 in the bar 3. The twist 9 in the wires 8 may extend as desired toward the indentations 7.

50 One fold of the wires 8 is coiled around the indentations 7 of the bar 3, as at 11. The wires 8 are provided with downwardly extending, normally diverging end portions 12 which terminate in the loops 13 constituting pairs of resilient clamping jaws for securing the free end portions of the legs of a pair of trousers therebetween. Rings 14 slidably 70 encircle the shanks 12 for moving the jaws 13 toward each other, as indicated in broken lines in Figure 3 of the drawing.

55 It will thus be seen that a garment hanger has been provided which is particularly adapted to accommodate a coat or similar body garment and a pair of trousers. In addition to providing means for supporting the trousers, the wires 8 materially strengthen the frame 1 as will be obvious.

60 It is believed that the many advantages of a garment hanger in accordance with the present invention will be readily understood, and although the preferred embodiment of the invention is as illustrated and described, 75 it is to be understood that changes in the details of construction and in the combination and arrangement of parts may be resorted to which will fall within the scope of the invention as claimed.

65 What is claimed is:—

70 1. A garment hanger comprising a substantially triangular frame including a pair of converging arms and a connecting bar, wires folded upon themselves and connected to the arms and to the bar, the folds of said wires terminating, at their free ends, in normally diverging shanks extending downwardly from the bar for clamping a garment 75 therebetween, and a ring slidably encircling 80

85 90 95 100

the shanks for moving said shanks toward each other and securing the same in clamping position.

2. A garment hanger comprising a substantially triangular frame including a pair of converging arms and a connecting bar, wires folded upon themselves and connected to the arms, one of the folds of each wire being connected to the bar, the folds of the wires terminating, at their free ends, in normally diverging pairs of shanks extending downwardly from the bar for clamping a garment therebetween, and rings slidably encircling the pairs of shanks for moving said pairs of shanks toward each other.

3. A garment hanger comprising a substantially triangular frame including a pair of converging arms and a connecting bar, wires folded, at an intermediate point, about the arms, the folds of said wires being twisted upon themselves for a portion of the lengths of said folds, one of the folds of each wire having an untwisted portion connected to the bar of the frame, the folds of said wires terminating, at their free ends, in normally diverging shanks extending downwardly from the bar for yieldingly clamping a garment therebetween, jaws on the ends of the shanks, and rings slidably encircling the pairs of shanks for moving said pairs of shanks toward each other to operative position.

4. A garment hanger comprising a substantially triangular frame including a pair of converging arms and a connecting bar, wires folded, at an intermediate point, about the arms, the folds of the wires being twisted upon themselves for a portion of their length, the folded and twisted wires being twisted about each other, one of the folds of each wire being connected with the bar of the frame, said folds terminating in normally diverging pairs of shanks extending downwardly from the bar and constituting clamping jaws for securing a garment therebetween, and means for moving the jaws to operative position.

5. A garment hanger comprising a substantially triangular frame including a pair of converging arms and a connecting bar, said connecting bar having spaced indentations therein, wires folded, at an intermediate point, about the arms, the folds of said wires being twisted upon themselves for a portion of their length, one of the folds of the wires being coiled about the indentations for connecting said wires to the bar, the folds of the wires terminating, at their free ends, in normally diverging pairs of shanks extending downwardly from the bar for yieldingly clamping the garment therebetween, jaws on the shanks, and rings slidably encircling the pairs of shanks for moving said pairs of shanks to operative position and for securing the same in operative position.

6. A garment hanger comprising a sub-

stantially triangular frame including a pair of converging arms and a connecting bar, said connecting bar having spaced indentations therein, wires folded, at an intermediate point, about the arms, the folds of the wires being twisted upon themselves for a portion of their length, the wires being twisted together and extending from the last named twist toward the indentations in the bar, one of the folds of the wires being coiled around the indentations, the folds of the wires terminating, at their free ends, in normally diverging pairs of shanks extending downwardly from the bar, jaws formed integrally with the free ends of the shanks, said jaws adapted to clamp a garment therebetween, the rings slidably encircling the pairs of shanks for moving the jaws toward each other.

In testimony whereof I affix my signature. 85
FRANK BORRIELLO.
